WELL BAILING DEVICE

Filed March 26, 1929

UNITED STATES PATENT OFFICE

BOYD K. APPLEMAN, OF BEAUMONT, TEXAS

WELL BAILING DEVICE

Application filed March 26, 1929. Serial No. 350,013.

My invention relates to new and useful improvements in a device for bailing deep wells.

The object of my invention is to provide a well bailing device in which the danger of overloading the device regardless of how deeply it may be submerged in the liquid within the well may be avoided thereby eliminating the danger of its being torn loose from the lifting mechanism as well as the expense and loss of time that would otherwise follow in the event of its disengagement.

Another object of my invention is to provide a sealing device for deep well bailing of a width and of a character which is not only more suitably adapted to pass over gaps at the joints of the well casing which oftentimes reach a space as much as one-half inch to five-eighths inch, but to also in a great measure balance said sealing device against excessive hydraulic pressure that would otherwise cause it to press against the casing with undue severity.

I accomplish the above stated purpose by the means disclosed in the accompanying drawings and specification, in which

Figure 1 is a composite plan elevation view almost wholly bisected longitudinally and chiefly in section, portions having been removed in order to disclose the arrangement and functions of inner working members.

Fig. 2 is a plan elevation of an elastic sealing ring partly shown on the same plane as in Fig. 1.

Fig. 3 is a top plan view of a cage type member shown directly opposite to its left in Fig. 1 while

Fig. 4 is a bottom plan view of the same member.

In Fig. 1 numeral 1 indicates a tubular casing such as is usually used for lining the inside of deep or drilled wells. Fig. 1 indicates the lower end of the tubing such as is usually employed for lowering bailing devices into and withdrawing them from the well and of its self constitutes no part of my invention.

A coupling 3, threaded within, serves to

attach my device to the aforesaid tubing, 4 is a tubular member of my device extending from AA to BB of Fig. 1 and carries with it collar 5 elastic sealing ring 6 and collar 7, said collars 6 and 7 being locked in position by sort metal pins 5½ and 7½ respectively. A second tubular member 8, extending from CC to DD is attached to member 4 and confines within it a tubular valve type cage 9 which in the position shown comes to rest with its upper end against the lower end of member 4 said cage 9 is provided with a valve seat 9½ at its upper end and a valve stem guide 10½ at its lower end and carries with it a poppet-type valve 10 along with a coil spring 12 which at its appointed time aids in seating valve 10. Cage 9 which has a free sliding fit in tubular member 8 has a limited downward movement during which it uncovers a series of port openings 11 in member 8 closing them again on its upward movement which is determined and controlled by a coil spring 13 which has a predetermined resistance and is supported at its lower end by a sleeve type member 14 which in turn is adjustably attached to tubular member 8. Sleeve 14 is closed at its lower end with cap 17 and is provided with a plurality of openings 14½ which serve as a strainer for preventing coarse matter from entering within the device. A further extension of casing 1 is shown along with coupling 16 in order to disclose a gap between the two sections and which in general practice usually varies from $\frac{1}{4}$ " to $\frac{3}{4}$ " and will be referred to in the description of operation.

In bailing wells of various depths and in order to sink the bailing device it is common practice to use an extension of about 60 feet of the tubing indicated by 2 in Fig. 1 of my device, the top of which is left open and to which an ordinary loop type of bail is attached for receiving a rope leading to the lifting mechanism thus providing an opening for the flow of liquid directly through the bailing device and out of the top of the tubing as the bailing device is being lowered into the well, also to permit of the liquid passing downward and through

the bailing device when not purposely intercepted by the mechanism of the bailing device itself.

For various reasons not necessary to mention here, much uncertainty frequently arises in determining just how far the bailing device is submerged below the top of the liquid in the well, and it is due to this fact that frequent overloading occurs, and often with dire results since a load approximating a vertical column of liquid of about 200 feet in depth is usually aimed at as a reasonably safe working load. An important factor also contributing to overloading develops from the tremendous pressure exerted upon the internal surface of the sealing device which in turn in a large measure increases its force of contact and friction as it engages with the well casing during excessive submergence. I overcome much of the latter by reducing the inner area of my sealing ring 6 Figs. 1 and 2 by providing it with a liberal number of openings $6\frac{1}{2}$, which passes a large share of said pressure direct to the casing. Further relief is afforded by beveling said ring over a reasonable area at or near its top and bottom edges, this beveling also being of value in adapting the ring 6 to glide smoothly over gaps at the joints of the well casing, such as are indicated within coupling 16 in Fig. 1, and which are subject to considerable variation. It will be noted however that the longitudinal depth of this ring must be ample to at all times overlap the gaps found at the joints between the two ends of the casing in order to at all times make a reasonably complete seal.

In Fig. 1 valve 10 is shown closed thus revealing the entire device as it would appear when starting downward, but prior to reaching the liquid in the well and at which point if not before, valve 10 is caused to open upward thereby permitting liquid to pass upward freely through the bailing device, as well as through and out of the top of the tubing 2 used in lowering it, and in which special care as to depth of submergence is quite unnecessary. When the operation is reversed valve 10 immediately closes and if the depth of submergence is such as to cause a liquid load greater than the predetermined load for which spring 13 is set, cage 9 along with valve 10 depresses spring 13 and moves downward opening ports 11, thereby permitting all excess liquid to pass outward through ports 11 and downward between the bailing device and well casing 1, thereby eliminating all danger of over loading the device.

When however the bailing device has been carried upward until the weight of liquid no longer exceeds the predetermined load for which spring 13 is set, said spring returns cage 9 to its original position, closing ports

11, and as valve 10 is also closed, all the liquid then remaining above the bailing device is carried out of the well during its upward movement. It will thus be seen that regardless of the depth of the submergence of the bailing device, the load resistance is not augmented but remains substantially the same under abnormal as well as under normal submergence, thus protecting the bailing device and connections thereto against undue strains or of the device being torn away from the lifting mechanism.

I am aware that there are a number of bailing devices in use; that are adapted to pass downward freely through the liquid in the casing which also includes valves that close during their upward movements, but I am not aware that any of them are provided with means for predetermining and controlling the maximum load or volume of liquid that may be carried upward and out of the well in a single operation regardless of the depth of the submergence of the bailing device.

I claim:

A deep well bailing device for operating in a casing, comprising a cylindrical element having collars disposed in spaced relation thereon, a packing ring surrounding said element and confined between said collars, the said ring being provided with a series of apertures and having its upper and lower sides beveled toward said element, whereby said ring may pass over open joints in said casing and will be substantially balanced against excessive hydraulic pressure.
